UNITED STATES PATENT OFFICE.

FRANK W. MILLER, OF CHICAGO, ILLINOIS, ASSIGNOR TO FRANCLARE COMPANY, OF CHICAGO, ILLINOIS, A CORPORATION OF ILLINOIS.

BOILER WASHING AND REFILLING SYSTEM.

Application filed March 10, 1921. Serial No. 451,105.

This invention relates to boiler washing and refilling systems, particularly of the type adapted for the handling of locomotives for purposes of blowing off, washing out, and refilling.

While systems of this general character have heretofore been employed in which the heat units of the blow-off water and blow-off steam have been utilized, the blow-off water being customarily used for washing out the locomotive boiler after it is blown off, and the blown off steam for heating clean, fresh water with which the locomotive is refilled, the time required to blow off, wash out, and refill a locomotive is so great, during which time the locomotive is necessarily out of service, that many railroads, instead of attempting to conserve the blow-off water and the heat units contained therein, simply blow off the steam from the dome of the locomotive, and use this steam for heating other water, while the blow-off water is permitted to run off to the sewer, or a sump.

One of the primary purposes of my present invention is to provide a system by which both the blow-off water and the blow-off steam may be conserved and the heat units thereof conserved and utilized, but furthermore, the system is adapted to very materially reduce the time required for the blowing off operation, so that the locomotive is required to be out of service for a minimum length of time only.

With this end in view, instead of blowing off the steam and water separately from the boiler, my invention contemplates a single blow-off connection to the lower part of the boiler, through which the water is blown off rapidly under the steam pressure in the boiler, thus freeing the boiler of its water in much less time than it would drain off by gravity. Furthermore, the rapidity of the blowing off operation, both during the time that the water is being discharged and subsequently, during the discharge of the steam, is greatly enhanced by creating in the blow-off line, a partial vacuum which expedites the discharge of both the water and steam from the boiler, and furthermore, this partial vacuum vaporizes a considerable portion of the blow-off water, with the result that a larger proportion of the blow-off products can be returned to the boiler for

refilling purposes than is possible when all of the water below 212° Fahrenheit must be delivered to the washout tank instead of to the filling tank, as is customary in systems now in general use.

Another object of my invention is the provision in a system of the character indicated, of means for cleaning the blowoff water and removing the sludge and dirt therefrom so that this water is in the best condition for use as washout water, the cleansing of the water being effected by an apparatus which does not involve the use of screens, filters, or other devices which quickly become clogged up and rendered ineffectual.

Another object of my invention is the provision of mechanism by which the sludge, dirt, and other solid matter removed from the blowoff products are automatically discharged from the system, thus relieving the operator of the necessity of manually attending to this operation, and furthermore, insuring that this sludge and sediment will be discharged from the system instead of being permitted to accumulate therein.

Another feature of my invention resides in the construction by which the water in the refilling line is continuously circulated so that it is always maintained at a high temperature in the drops, and this circulating water is reheated before being returned to the refilling tank by exhaust steam so that the temperature of the refilling water is not reduced by reason of prolonged circulation through a long refilling line.

Still another feature resides in the construction of the drops, and the employment of a single connection between the blow-off drop, the refilling drop, and the locomotive, so that it is not possible through carelessness of the operator, to destroy the vacuum in the blow-off line by leaving the blow-off drop valve open after the blowing off operation has been completed.

Other objects and advantages of this invention will be apparent as the same becomes better understood by reference to the following description, when considered in connection with the accompanying drawings:

Referring to the drawings—

Fig. 1 is a side elevation, partially in section of a system embodying my invention;

Fig. 2 is a plan view of the structure shown in Fig. 1;

Fig. 3 is a diagrammatic view, illustrating the layout of the structure shown in Fig. 1;

5 Fig. 4 is a fragmentary view showing the pipe layout at one of the stalls in the roundhouse;

10 Fig. 5 is an enlarged view, partially in section of the apparatus for producing a vacuum in the blow-off line;

Fig. 6 is an enlarged fragmentary view, showing the automatic sludge-dumping apparatus; and

15 Fig. 7 is an enlarged detail view of the connection between the blow-off and refilling drops.

Referring now to the drawings more in detail, reference character 8 indicates the washout tank, or the tank in which the water 20 for washing out the locomotive boilers is stored, and 9 indicates the refilling tank in which the clean fresh water to be employed in refilling the boiler is stored. These tanks, the pumps, and other apparatus embodied 25 in the system, are customarily arranged within a separate house or building 11, disposed in proximity to the roundhouse. A section of the roundhouse itself is illustrated in Fig. 4, and a locomotive to be treated is 30 run into the roundhouse over one of the pits 12 adjacent to a post 13, upon which the blow-off drop 14, the wash-out drop 15, and the refilling drop 16, are mounted. These drops are connected at their upper 35 ends with the blow-off line 17, the washout line 18, and the refilling line 19 respectively, which lines extend around the roundhouse to the various stalls therein, and are connected with the apparatus in the house 11 by 40 suitable lines 21, 22, and 23 respectively.

The blow-off line is connected with a centrifugal separator 24, which is devoid of screens and other parts which might become clogged up. The interior construction of 45 this separator which is not specifically claimed herein forms the subject matter of my co-pending application, Serial No. 257,120, filed October 7, 1918. The steam, blow-off water, and impurities such as 50 sludge, scale, and the like delivered from the boiler through the blow-off line to this separator, are there effectively separated one from the other, the solid matter being accumulated in the bottom of the separator, the water being delivered from the separator through a pipe 25 into the wash-out tank 8, and the steam being withdrawn from the top of the separator through a pipe line 26. Since the connection from the blow-off drop 55 to the boiler is made at or near the bottom of the boiler, it will be manifest that more water than steam will be blown off during the early part of the blowing off operation, this water being discharged with great rapidity under the pressure of the steam con-

tained in the boiler. For the purpose of expediting the discharge of the blow-off products from the boiler, and in order to convert a portion of this hot blow-off water into steam or vapor, my invention contemplates the application of a partial vacuum to the separator 24, this vacuum of course, being necessarily applied to the blow-off line 21, so as to reduce the pressure against which the boiler is blown off. The production 75 of the vacuum in the blow-off line is accomplished by means of a condenser, indicated generally by reference character 27, which condenser is preferably disposed at considerable elevation above the refill tank so that 80 water flowing from the condenser will attain considerable velocity in its descent to the refill tank, thus increasing the effective suction of the condenser upon the blow-off line.

The pipe 26 communicates with a vertical riser 28, which extends upwardly through and above the roof of the building, and is connected by means of an elbow 29 with the upper end of the injector condenser 27. The condenser is shown on an enlarged scale in Fig. 5, from which it will be observed that it comprises at its upper end, a chamber 31, beneath which is disposed a venturi 32. Water is supplied to the chamber 31 from a supply pipe 33, which receives its water from any suitable source of supply, preferably through a pipe 34, as shown in Fig. 1, which is connected to the city water supply, or to a pump. The water mixing in the 90 chamber 31 with the blow-off steam serves to partially condense the same, and the water flowing downwardly through the venturi 32, and thence through the pipe 35 into the refill tank 9, produces a suction upon the chamber 31, producing a partial vacuum which is communicated through the pipes 28 and 26 to the separator 24 and blow-off line 21. The suction created in the venturi is augmented by the velocity of the water below the venturi, with the result that a sufficiently high 95 vacuum is produced to permit the rapid blowing off of the water and steam from the boiler, and also to partially vaporize the hot water in the separator, with the result that a greater quantity of steam is delivered in condensed form to the refill tank than was originally contained in the boiler. Thus not only is the rapidity of the blowing off 100 operation greatly increased, but the quantity of the blow-off products delivered to the refill tank where they are available for refilling purposes is greater than in any other 105 systems with which I am familiar.

If for any reason the venturi should become stopped up or should fail to relieve the pressure in the line 26, the steam will be delivered directly into the refill tank 9 through the branch 36 which extends downwardly into the tank and delivers the steam 110

below the water level, thus heating the water in the tank. To prevent accidental accumulation of excess pressure or the production of a vacuum in the tank, a vent pipe 37 leads 5 from the top of the tank directly to atmosphere.

The pipes 35 and 36 delivering into the refill tank, and also the pipe 25 delivering into the washout tank, are equipped at a 10 suitable distance below the normal water level in the respective tanks with delivery devices 38, including one or more downwardly inclined branches 39, through which delivery from these pipes takes place. The 15 pipes at their lower ends are equipped with suitable pedestals 40, resting upon the bottom of the respective tanks, and preferably that portion of each pipe below the delivery devices is filled with cement or other suitable 20 material, as indicated at 50, thus closing this portion of the pipe, and in fact, providing a supporting column for the upper portion thereof.

Should the supply of water to the refill 25 tank through the venturi be insufficient to supply the demands on the tank, additional water may be delivered directly from the cold water pipe 33 through a branch 41, equipped with a balanced valve 42 adapted to be actuated by a float 43, so that this valve 30 will open when the water level in the tank 9 falls below a predetermined height; also, to guard against overflowing of the tank, a similar balanced valve 44 is interposed in the pipe 33 and controlled by a float 45 to 35 shut off the supply of water to the condenser when a predetermined water level in the tank 9 has been reached.

The water in the washout tank 8 is withdrawn therefrom for washout purposes 40 through a pipe 46 by a steam pump 47, by which it is delivered through the delivery pipe 48 to the washout line 22. In order that this water may be automatically tempered down to a temperature at which the nozzle can be handled by the washer, I have provided a connecting pipe 49 between the cold water pipe 33 and the intake pipe 46, and in this pipe 49, there is interposed a thermostatically-controlled valve 51 adapted to be opened and closed by a thermostat 52 disposed in the delivery pipe 48. Should the temperature of the water delivered by the pump 47 through the pipe 48 be higher than that desired for washout purposes, the valve 51 will be automatically opened to admit a sufficient quantity of cold water to the inlet of the pump to temper down water withdrawn from the tank 8 so that the washout water will be delivered at the requisite temperature. The pipe 33 also has a branch 53 extending into the washout tank 8 to supply water thereto in case there is insufficient water supply from the blowoff products

through the pipe 25. A valve 54 interposed in pipe 33 is controlled by a float 55, which opens the valve, admitting cold fresh water when the water level in the tank 8 falls to a predetermined point. The pump 47 is operated by steam supplied through a steam line 56 from the power boilers, the steam being delivered to the pump through a branch 57, and the exhaust from the pump is delivered through a pipe 58, which is connected at 59 with the line 26 so that the exhaust steam, as well as the blowoff steam is delivered to the condenser. The refill pump 61 is likewise supplied with steam from the line 56 through a branch 62, and the exhaust from this pump is conducted by a branch 63 into the pipe 58, all as shown in Fig. 1. To preclude any appreciable back pressure in this exhaust line, a vent pipe 64 is connected therewith and adapted to vent to atmosphere, this pipe being equipped with a balanced valve 65, which is adapted to automatically open when the pressure in the exhaust line becomes too high.

The refilling water is withdrawn from the tank 9 by the pump 61 through an intake pipe 66, and is delivered therefrom through the discharge pipe 67 into the refill line 23, as shown. To take care of any overflow from the tank 9, a pipe 68 rises from the pipe 66, and this pipe is equipped with a float-controlled valve 69 which opens only when the water in the tank rises to a predetermined height. When overflow takes place, the water flows from the pipe 68 through a horizontal pipe 71 from whence it is discharged through a branch 72 into the drain pipe 73, connected at one end with the refill tank and at its other end with the washout tank, as shown in Fig. 1. Either of the tanks may be drained by opening one or the other of the drain valves 74 or 75, the drainage being discharged to the sewer through a common pipe 76. The washout tank is also adapted to overflow through a vertical riser 77 connected with the intake pipe 46, and at its upper end with the pipe 71, overflow through this pipe being likewise controlled by a float 78. In order to prevent siphonage from the tanks, pipes provided with check valves 79 and 81 are connected with the upper ends of the risers 77 and 68 respectively. The formation of a vacuum or the accumulation of an excess pressure in the washout tank is obviated by a vent pipe 82 from the top thereof.

The sludge, scale, sediment and other solid matter collected in the bottom of the separator 24 from the blowoff products are delivered from this separator into the sewer pipe 83 by a delivery pipe 84. For the purpose of automatically effecting the discharge of this accumulated matter from the separator without the attention of the operator,

I have provided automatic mechanism for accomplishing this result, which will now be explained.

Referring to Fig. 6, wherein this mechanism is best shown, it will be observed that upon the side of the separator there is slidably mounted a pipe 85, carrying a float ball 86, the pipe and float ball being adapted to move up and down in the guides 87. Communication is established between the interior of the separator and the pipe 85 and float ball 86 through a connection 88 including a flexible hose 89, which permits of the vertical movements of the float. The top of this connection is substantially on a line with the water delivery pipe 25 from the separator to the washout tank so that when at the beginning of a blowing off operation the water level in the separator reaches the height of this pipe 25 and begins to overflow into the washout tank, water will flow through the connection 88 into the float ball, and when the weight of the water added to the weight of the float ball and pipe becomes sufficient, it will overbalance a weight 91 carried by a lever 92 connected to a shutoff valve 93, a rod 94 serving to transmit motion of the float ball to the lever 92 so that the parts will assume the position indicated in dotted lines in Fig. 6, thereby closing the valve 93.

Valve 93 is interposed in a pipe 94 connected at its upper end to a large pipe 95 which in turn is connected with the pipe 25 through a smaller pipe 96. When water flows through the pipe 25, the chamber 95 will become filled and when the valve 93 is closed as above explained, this water will be trapped in the chamber 95.

A flexible hose 97 connects the valve 93 with a float ball 98 carried by a pipe 99 guided for vertical reciprocation in guides 101 similar to the guides 87 for the pipe 85. The float 98 is connected by a rod 102 with a lever 103 attached to a shutoff valve 104, and carrying a counterweight 105. This valve 104 is disposed in a bypass 106 of the discharge pipe 84, and is normally maintained in closed position, as shown in full lines in Fig. 6 by the weight 105.

During the blowing off operation, or so long as the separator 24 is overflowing into the tank 8, the float 86 is kept filled with water, thus maintaining the valve 93 in closed position, the valve 104 in the meantime being maintained in closed position by the weight 105. When, however, the blowing off operation has been completed, so that the water level in the separator falls below the inlet of the connection 88, no more water will enter ball 86 through connection 88 consequently the water contained in the float ball 86 will empty through the pipe 107 into the tank 8, a flexible hose 108 being interposed in the connection between this pipe and the

float ball. When the water is emptied out of the float ball, the counterweight 91 will return the parts to the position shown in full lines in Fig. 6, thereby opening the valve 93 and permitting the water which has been trapped in the chamber 95 to flow into the float ball 98, thereby causing this float to lower so as to open the valve 104 and permit the sludge and water to drain from the separator through the pipe 84. The water then empties from the float ball 98 thru a restricted opening into a pipe 109 connected with the bottom of the float and with the pipe 106, a flexible hose connection 111 being interposed in the connection to permit the vertical movements of the float ball. When the float ball has been emptied, the weight 105 will thereupon close the valve 104, thus closing the bottom of the separator so that it is ready to again receive blowoff products. It will be apparent, therefore, that this mechanism automatically provides for flushing out of the separator after each blowing off operation, and that this operation is performed entirely automatically, and that the parts are automatically restored to normal position so that no attention on the part of the operator is required. In order that the separator may be drained at will, a hand-operated shut-off valve 112 is interposed in a branch 113 between the separator and the pipe 84, and this valve which is normally closed, may be opened by the operator to drain the separator at any time he may consider it advisable.

For purposes of maintaining the refilling water in the refilling line at the requisite temperature, the end of this line in the roundhouse is connected, as indicated at 114, (Fig. 4) to a circulating line 115, which through a line 116, connects with the cold water pipe 33, as shown in Figs. 1 and 3. The water which is continuously circulated through the refill line and back through this circulating line by the pump 61, which operates slowly when refilling is not taking place, is thus delivered to the condenser 27, where it condenses the exhaust steam from the pumps when no blowingoff operation takes place, and this water, together with the condensed steam, is delivered to the refill tank through the pipe 35, thus serving to heat this water and keep it at the proper temperature and at the same time, the water in the refill line is kept at the proper temperature without diminishing the supply in the refill tank.

The water in the washout line is also maintained at the proper temperature by recirculating it through the blowoff line, the connection between the blow-off line and the refilling line being indicated in Fig. 4 by reference character 117.

Since a constant vacuum is maintained in the blowoff line by the condenser 27 when a

boiler is being blown off, it is desirable that this vacuum be not broken or destroyed, as would be the case if a valve at one of the drops 14 were left open, thus opening the blowoff line to atmosphere. For the purpose of reducing this possibility, which might result from the carelessness of the operators in the roundhouse, I have provided a cross-connection 118 between the lower ends of the blowoff drops 14 and the refill drops 16, as indicated by reference character 118 in Figs. 4 and 7, and instead of employing two hoses, one connected to each drop, I employ one hose 119 attached to the connection 118 through which both the blowing off and refilling operations are accomplished. The drop 14 is provided with a shutoff valve 121, and the refill drop 16 is provided with a similar shutoff valve 122. After the blowing off operation has been completed, should the operator fail to close the shutoff 121 in the blowoff drop, when the refilling operation is begun the refill water, or at least a large proportion thereof, instead of being delivered to the locomotive through the hose 119 will be drawn up the blowoff drop into the blowoff line. This serves to prevent the breaking of the vacuum in the line, and since the boiler will not fill, the operator will soon discover his failure to close the shutoff valve 121. It will be apparent, therefore, that instead of destroying the vacuum in the blowoff line, as would be done under normal circumstances if the blowoff drops were not all closed, I am by this cross-connection and the employment of a single hose, enabled to insure against the breaking of the vacuum in the blowoff line except at such time as may intervene between the blowing off and the refilling of any particular boiler, and even if some water from the refill line should be drawn back into the blowoff line, no harm would be done, and the fact that the blowoff drop is open will quickly become apparent to the operator, who will thereupon close it.

In the operation of my improved system, a locomotive is run into position over one of the pits, whereupon the hose 119 is connected with the boiler near its bottom, the valve 121 is opened, and the products are blown off from the boiler under the steam pressure therein, the rapidity of the blowing off being augmented by the vacuum produced by the condenser 27. From the separator the blowoff water is delivered to the washout tank, and the steam to the refill tank, where the washout and refill waters are respectively stored. After the blowoff operation, the boiler is washed out by means of a hose and nozzle connected to the washout drop, whereupon the refill valve 122 is opened and the boiler is refilled by the clean, fresh water from the refill tank. After each blowing off operation, the separator is

automatically flushed out to relieve it of the sludge and sediment accumulated therein. The water in the refill line is continuously circulated and kept at the required temperature, the exhaust steam from the pumps 70 is utilized in maintaining a vacuum on the blowoff line and in heating the water in the refill tank, and suitable provision is made for overflow from both tanks and for prevention of the formation of a vacuum or the 75 accumulation of an excess pressure in either tank. A system embodying my invention is extremely economical and efficient in operation, and the time that the boiler need be out of service for purposes of 80 blowing off, washing out, and refilling, is very materially reduced over any system with which I am familiar.

It is believed that my invention, its construction, mode of operation, and many of 85 its inherent advantages will be understood and appreciated from the foregoing without further description, and it should be manifest that the details of construction shown and described are capable of wide 90 modification without departing from the essence of the invention, as defined in the following claims.

I claim:

1. In a boiler washing and refilling system, the combination of a blowoff line for conducting the blowoff steam and water from a boiler, means communicating with said blowoff line for separating said steam and water and removing the solids from 100 said water, a washout tank, means for delivering said water to said washout tank, a refill tank, means for delivering said steam to the refill tank, means for producing a suction on said blowoff line to expedite the 105 blowoff operation and vaporize a portion of said blowoff water and means for preventing the counter-action of the suction in said blow off line when said blowoff and refill lines are simultaneously open. 110

2. In a boiler washing and refilling system, the combination of a blowoff line through which the steam and water are blown off from a locomotive boiler, means in said line for separating the blown off 115 steam and water, a washout tank, means for conducting the blowoff water to said washout tank, a refill tank, means for conducting the blowoff steam to said refill tank, means acting on said steam to condense the 120 same and reduce the back pressure in said blowoff line whereby to expedite the blowing off operation, a refill line, and means for sealing the blowoff line against atmosphere when the refill line is in operation. 125

3. In a boiler washing and refilling system, the combination of a blowoff line, a separator therein, means for automatically causing the discharge of sludge from said separator when the water in the separator 130

rises above a predetermined level, a washout tank, means for conducting blowoff water from said separator to said washout tank, a refill tank, means for conducting the steam from said separator to said refill tank, a jet condenser disposed in said last mentioned means, means for supplying water to said condenser, and means controlled by the water level in said refill tank for shutting off the water from said condenser.

4. In a boiler washing and refilling system, the combination of a blowoff line through which steam and water are blown off from the locomotive boiler, means interposed in said line for separating the sludge from said water and for separating the steam therefrom, a washout tank, a pipe for conducting the blowoff water from said separator to said washout tank, a pipe for delivering the sludge from said separator, a pipe for delivering the steam from said separator, means connected with said last mentioned pipe for producing a suction therein to reduce the pressure in the blowoff line, means for ensuring the closure of the blowoff line to thereby prevent the counteraction of the suction producing means during a refilling operation, a refill tank, means for delivering said steam into said tank and means controlled by the water level in the refilling tank for controlling said suction means.

5. In a boiler washing and refilling system, the combination of a washout tank, a refill tank, a blowoff line, a separator in said line, means for conducting the blowoff water from said separator to the washout tank, a jet condenser mounted at a considerable height above said refill tank, a pipe connecting said separator and said condenser through which steam is withdrawn from said condenser, means for preventing entrance of atmospheric air into the condenser through the blowoff line during a refilling operation, a pipe for supplying water to the condenser, a pipe leading from said condenser directly into said refill tank through which the condensation products are delivered into said tank and means for automatically draining said separator after each blowing off operation.

6. In a boiler washing and filling system, the combination of a washout tank, a refill tank, a blowoff line, a separator therein, a pipe for delivering water from said separator to said washout tank, a steam pipe leading from said separator into said refill tank and opening therein below the water level in said tank so that discharge from said pipe into said tank must overcome the water head above said opening, a pipe extending upwardly from said steam pipe, a condenser connected therewith at a considerable height above the refill tank, means for supplying water to said condenser, and means for de-

livering the discharge from said condenser directly into said refill tank.

7. In a boiler washing and refilling system, the combination of a washout tank, a refill tank, a blowoff line, a separator for 70 separating the blowoff products from the locomotive, means for conveying the blowoff water from said separator to said washout tank, a condenser, means for conveying the blowoff steam from said separator to said condenser, a pump, an exhaust steam pipe therefrom connected to deliver to said condenser, means for supplying water to said condenser to condense said steam and thereby reduce the pressure in said blow off line, so means for preventing entrance of air into the blow off line thereby precluding impairment of the pressure reduction during a refilling operation, and a pipe for delivering the condensation products from said condenser to said refill tank.

8. In a boiler washing and refilling system, the combination of a washout tank, a refill tank, a blowoff line, a separator therein, a washout line, a refilling line, 90 pumps for delivering water from said tanks to said washout and refilling lines respectively, a condenser, a blowoff steam pipe leading from said separator to said condenser, means for supplying water from 95 one of said lines to the condenser, means for delivering condensation products from said condenser to said refilling tank, a pipe for delivering blown off steam directly from said steam pipe into said refilling tank below the 100 water level therein and means for automatically draining the separator after each blowing off operation.

9. In a boiler washing and refilling system, the combination of a blowoff line, a 105 separator therein, means for delivering the blowoff water from said separator, means for delivering the blowoff steam from said separator, a condenser into which said blowoff steam is delivered, a cold water pipe, a 110 connection between said pipe and said condenser, a refill tank, a connection between said condenser and said refill tank, a connection between said cold water pipe and said refill tank, means controlled by the 115 water level in said tank for controlling the supply of water from said cold water pipe to said condenser and means controlled by the water level in said tank for controlling the delivery of water from said cool water 120 pipe through said connection directly to said tank.

10. In a boiler washing and refilling system, the combination of a refill tank, a blowoff line, means for separating the blowoff steam and water, means for exerting a suction on said blowoff line, means for preventing the breaking of said suction, means for delivering the blowoff steam to said refill tank, means for preventing the forma- 125 130

tion of a vacuum in said tank, and means for maintaining a predetermined water level in said tank.

11. In a boiler washing and refilling system, the combination of a blowoff line, a separator therein, a washout tank, means for delivering blowoff water from said separator to said washout tank, means controlled by a blowoff product for automatically draining said separator after each blowing off operation, a refill tank, means for delivering blowoff steam from said separator to said refill tank, a condenser for exerting a suction upon said separator and for condensing the steam delivered from said separator, means for delivering said condensed steam to said refilling tank, and means for supplying water to said refill tank.

12. In a boiler washing and refilling system, the combination of a refill tank, a blowoff line, a separator therein, means for exerting a suction on said separator to withdraw the blowoff steam therefrom, said last mentioned means including a condenser, means for maintaining the blow off line closed during a refilling operation to prevent the breaking of the vacuum therein, a refilling line, means for delivering water from said refill tank to said refilling line, and a circulating line connected with the end of said refilling line and with said condenser through which water is returned from said refilling line to said condenser, and a connection from said condenser to said refill tank.

13. In a boiler washing and refilling system, the combination of a washout tank, a refill tank, a blowoff line, a separator therein, means for conducting the blowoff water from said separator to said washout tank, means for conducting the blowoff steam from said separator to said refill tank, said last mentioned means including a steam condenser, a wash out line, means for delivering water from said wash out tank to said wash out line, a refilling line, means for delivering water from said refill tank to said refilling line, a circulating line connecting the end of said refill line with said condenser, means for supplying additional water to said condenser, means controlled by the water level in said refill tank for controlling the supply of said additional water to the condenser.

14. In a boiler washing and refilling system, the combination of a washout tank, a refill tank, a washout pump, a refill pump, an intake pipe connecting said washout tank with said washout pump, an intake pipe connecting said refill tank to said refill pump, a riser pipe connected with each of said intake pipes, a cross-connecting pipe between said riser pipes approximately at the top of the tanks, and an overflow de-

livery pipe connected with said cross connecting pipe.

15. In a boiler washing and refilling system, the combination of a washout tank, a washout pump, an intake pipe leading from said washout tank to said pump, a washout line to which said pump delivers, a refill pump, an intake pipe connecting said refill tank with said refill pump, a refilling line to which said refill pump delivers, a riser pipe extending upwardly from each of said intake pipes, a cross-connecting pipe connecting the upper ends of said risers, a water level controlled valve disposed in each of said risers, and a delivery pipe connected with said cross-connecting pipe.

16. In a boiler washing and refilling system, the combination of blow-off, washout, and refilling lines, a separator interposed in said blowoff line, a washout tank, means for delivering blowoff water from said separator to said washout tank, a refill tank, a connection between said separator and said refill tank through which the blowoff steam is delivered, means for inducing a suction in said connection to reduce the pressure in said separator, a pump for delivering water from said washout tank to said washout line, means disposed in said washout line for automatically tempering the water delivered to said line, a pump for delivering water from said refill tank to said refilling line, a connection between said refilling line and said suction producing means, and means for automatically flushing said separator after each blowing-off operation.

17. In a boiler washing and refilling system, the combination of a blowoff line through which the steam and water are blown off from a locomotive boiler, a round-house drop connected to said line, a refilling line, means for supplying refill water to said line, means for inducing a vacuum in said blowoff line and drop, a refill drop connected with said refilling line, a valve for each of said drops, and a valveless connection between said drops for preventing the breaking of the vacuum in the blowoff line during a refilling operation in the event that the valve in said blowoff drop should be left open.

18. In a boiler washing and refilling system, the combination of a blowoff line, a drop connected thereto, a valve in said drop, means for inducing a vacuum in said blowoff line and drop, a refilling line, means for supplying refilling water thereto a drop connected with said refilling line, a valve in said drop, and a cross-connection between said blowoff and refill drops.

19. In a boiler washing and refilling system, the combination of a blowoff line, a drop connected therewith, means for inducing a vacuum in said line and drop, a re-

filling line, a drop connected thereto, means for supplying refilling water to said refilling line, valves in said drops, a cross-connection between said blowoff and refill drops, and a hose attached to said connection through which a boiler may be blown off and refilled.

20. In a boiler washing and refilling system, the combination of a blow-off line, a separator connected therewith, a discharge pipe from said separator, a valve in said pipe, a movable ball adapted when filled with water to open said valve, a chamber adapted to contain a quantity of water to be delivered to said ball, and means controlled

by the water level in said separator for admitting water from said chamber to said ball.

21. In a boiler washing and refilling system, the combination of a blowoff line, a separator therein, a discharge pipe from said separator, a valve in said pipe, a float ball adapted to open said valve, a chamber for supplying water to said float ball, a valve interposed between said chamber and said float ball, and a second float ball connected with said separator and adapted to close said last mentioned valve when a predetermined water level is produced in said separator.
